US00D891945S

(12) **United States Design Patent** (10) **Patent No.:** **US D891,945 S**
(45) **Date of Patent:** **** Aug. 4, 2020**

(54) **SMART CONTROL PANEL**

- (71) Applicant: **HDL Automation Co., Ltd.**,
Guangzhou, Guangdong (CN)
- (72) Inventor: **Mei Xiao**, Guangdong (CN)
- (73) Assignee: **HDL Automation Co., Ltd.**,
Guangzhou (CN)

(**) Term: **15 Years**

(21) Appl. No.: **29/648,315**

(22) Filed: **May 21, 2018**

Related U.S. Application Data

(63) Continuation of application No. 29/598,083, filed on
Mar. 23, 2017, now abandoned.

(30) **Foreign Application Priority Data**

Jan. 5, 2017 (CN) 2017 3 0004063

Primary Examiner — Selina Sikder

(57) **CLAIM**

The ornamental design for a smart control panel, as shown and described.

DESCRIPTION

FIG. 1 is a front elevational view of a smart control panel showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top and rear perspective view thereof;

FIG. 8 is a bottom and rear perspective view thereof;

FIG. 9 is a front and left side perspective view thereof;

FIG. 10 is a top, rear and right side perspective view thereof; and,

(Continued)

FIG. 11 is a bottom, rear and left side perspective view thereof.

1 Claim, 11 Drawing Sheets
